ELECTRIC SWITCH HOUSING

Rudolf Popp, Valparaiso, Ind., assignor to McGill
Manufacturing Company, Inc., Valparaiso, Ind.,
a corporation of Indiana

Application November 2, 1951, Serial No. 254,467

4 Claims. (CL. 200—168)

1

The present invention relates to electric switches, and more particularly to electric switch assemblies of the type comprising a preassembled switch mechanism and a separable housing therefor.

In order to achieve economy in the manufacture of small electric switches, the number of individual parts such as stampings and moldings should be reduced to a minimum and the assembled design of such parts should facilitate easy assembly with consequent saving in labor costs. Also, in the interests of safety the assembled switch should be so designed that the switch mechanism is completely enclosed and no extraneous metal parts are presented for inadvertent electric contact with the strands of conductor wires after the switch is wired in a circuit. However, the design of the preassembled switch mechanism and housing therefor should be such that the switch mechanism may be readily exposed for purposes of wiring the switch in a circuit.

It is an object of the invention to provide an improved form of electric switch assembly comprising a preassembled switch mechanism and a separable housing therefor which may be readily assembled into a fully enclosed unit and which employs a minimum number of separable elements to be assembled.

Another object of the invention is to provide an improved design of electric switch mechanism for facilitating the assembly of a switch housing and preassembled switch mechanism to form in the assembled relation, a fully enclosed unit.

A feature of the invention is the provision of an outer switch housing having a side wall opening through which a preassembled switch mechanism may be received to be enclosed, the housing further having an aperture in a portion of its wall opposite the side wall opening to permit the passage therethrough of an operating member of the switch mechanism. The switch mechanism according to the invention, is further provided with a cover member carried therewith to automatically close the side wall opening of the housing when assembled in the housing by the simple expedient of dropping the switch mechanism therein with its operating member passing through the aperture of the housing.

Further objects, features and the attending advantages of the invention will be apparent with reference to the following specification and drawings, in which:

Fig. 1 is a perspective elevational view of the assembled switch housing and preassembled switch mechanism;

2

Fig. 2 is an exploded view to show the assembly of the preassembled switch mechanism and housing, the housing being shown in longitudinal section;

5 Fig. 3 is a view similar to Fig. 2, but showing the assembled relation of the preassembled switch mechanism and the housing;

Fig. 4 is an end view partly in section to show the assembled relation in the switch housing of 10 the cover plate carried by the preassembled switch mechanism; and

Fig. 5 is a detailed perspective of the stamped cover plate.

The electric switch of the present invention 15 providing a closed insulatingly housed unit is comprised of three principal components, an outer switch housing, an inner preassembled switch mechanism, and a locking member for securing together the switch mechanism and housing. The preassembled switch mechanism may be of the type comprising a pair of frame side members between which are secured switch contacts and operating mechanism therefor. A switch operating member extends radially from

20 25 housing. The outer housing is preferably formed or molded in one piece of cup-shape having an open mouth or side wall opening through which the preassembled switch mechanism may be received. An aperture in a wall of said housing opposite to the side wall opening is provided through which the operating member of the switch mechanism may extend. After the preassembled switch mechanism

30 35 40 45 50 is inserted in the outer housing by the simple operation of dropping it therein with the operating member extending through the aperture of the housing, the locking member may be secured thereto to lock the final assembly. According to the invention, a cover plate is secured to and carried by the preassembled switch mechanism in a manner to close the side wall opening of the outer housing when the preassembled switch mechanism is enclosed therein. The cover plate may be provided with cut-out portions of a size

to permit the passage therethrough of the connecting wires to the contacts of the switch. When wiring the switch in a circuit, the wires may be easily connected to the switch by disassembling the switch mechanism and the separable housing.

Referring to the drawings, the electric switch is comprised of the outer cup-shaped housing 10, an inner preassembled switch mechanism generally shown at 11 and the threaded collar locking means 12 for securing the assembled relation of the switch. The preassembled switch mechanism

11 may be comprised of a plurality of switch contacts and operating mechanism not shown, but enclosed between the frame side plate members 13 and 14. Details of the switch contacts and operating mechanism have not been shown inasmuch as they are not part of the present invention. However, if a more detailed understanding of a suitable form of preassembled switch contact mechanism is desired, reference may be had to my prior Patent 2,068,701, issued January 26, 10 1937.

The outer housing 10 is preferably molded in one piece of insulating plastic material in a form to closely surround the side plates 13 and 14 of the preassembled switch mechanism 11. The 15 housing 10 is preferably cup-shaped to provide a mouth or side wall opening 15 through which the preassembled switch mechanism 11 may be received. An aperture 16 is also formed in a wall of the housing 10 opposite to the mouth or side 20 wall opening 15. The preassembled switch mechanism 11 has a threaded neck portion 17 extending radially therefrom and encloses a switch actuating member 18, together with the operating 25 chain 19. The preassembled switch mechanism 11 is adapted to be assembled within the housing 10 with the threaded neck portion 17 of the switch mechanism extending through the aperture 16. Thereafter, the lock nut 12 may be 30 threaded on the neck portion 17 to secure the assembled relation of the switch as shown in Fig. 3.

In order to close the mouth or side wall opening 15 of the outer housing 10 a cover plate 20 is secured to the preassembled switch mechanism 11. In the preferred form of the invention the cover 35 plate 20 is secured between the side plates 13 and 14 by means of its projecting portions 21 and 22 which extend into suitable openings 23 and 24 of the side plates 13 and 14, respectively. The cover plate 20 is preferably a unitary stamping 40 of fiber board or other insulating material and the cut-out portions 25 and 26 may be stamped from the cover to permit the passage of electric wire into the housing 10 to the inner switch contacts.

With particular reference to Fig. 2 of the drawings it will be seen that a simple and economical form of electric switch has been provided by this invention. To complete a final assembly of the preassembled switch mechanism into the form of a completely enclosed unit it is only necessary to drop the preassembled switch mechanism 11 into the housing 10 and secure the assembled relation by means of a lock nut. The cover plate 20 which is carried by the switch mechanism 11, 55 automatically closed the mouth or side wall opening 15 of the housing 10 through which the preassembled switch mechanism 11 has been inserted. It should be apparent that when the housing 10 and cover plate 20 are formed of insulating material, the assembled form of outer housing and preassembled switch mechanism with attached cover plate has no exposed metal parts to which stray wires or strands of conductors may become short circuited. Inasmuch as a single one-piece outer housing and a simple stamped unitary cover plate carried by the preassembled switch mechanism are the only elements necessary to fully enclose the switch it should be understood that the manufacturing economy involved in the production and assembly of the switch is greatly improved.

Various modifications may be made without departing from the spirit and intended scope of the appended claims.

I claim:

1. In an electric switch assembly which has a switching mechanism with an operating means therefor projecting therefrom, the combination of a pair of spaced frame plates disposed on either side of the switching mechanism and supporting the switching mechanism therebetween with the operating means extending out from one edge of each of said frame plates, each of said frame plates having an aperture therein adjacent the edge thereof opposite the first mentioned edge, a housing having an open end for receiving said frame plates with the switching mechanism supported therebetween, said housing having an aperture in its end opposite said open end and through which the operating means for the switch mechanism protrudes, and an insulating cover member having a pair of ears respectively extending into the aforementioned apertures in said frame plates to support said cover member between said frame plates, said cover member having a configuration corresponding to the aforementioned open end of said housing to enclose said open end.

2. In an electric switch assembly which has a switching mechanism with an operating means therefor projecting therefrom, the combination of a pair of spaced parallel frame plates disposed on either side of the switching mechanism and supporting the switch mechanism therebetween with the operating means extending out from one edge of said frame plates, each of said frame plates having an aperture therein adjacent the edge thereof opposite the first mentioned edge, a molded one-piece housing having a pair of spaced parallel sides and an open end for receiving said frame plates with the switching mechanism supported therebetween and with said frame plates disposed adjacent respective ones of the spaced parallel sides of said housing, said housing having an aperture in its end opposite said open end and through which the operating means for the switch mechanism protrudes, and an insulating cover plate having a pair of ears respectively extending into the aforementioned apertures in said frame plates to support said cover between said frame plates and perpendicular thereto, said cover having a configuration corresponding to the aforesaid open end of said housing to enclose said open end and also having edge notches to receive electrical conductors adapted to be connected to the switching mechanism.

3. In an electric switch assembly which has a switching mechanism with an operating means therefor projecting therefrom and a threaded collar surrounding the operating means, the combination of a pair of spaced parallel frame plates disposed on either side of the switching mechanism and supporting the switching mechanism therebetween with the operating means extending out from one edge of said frame plates, each of said frame plates having an aperture therein adjacent the edge thereof opposite the first mentioned edge, a molded one-piece housing having a pair of spaced parallel sides and an open end for receiving said frame plates with the switching mechanism supported therebetween and with said frame plates disposed adjacent respective ones of the spaced parallel sides of said housing, said housing having an aperture in its end opposite said open end and through which the operating means and surrounding collar protrude, an insulating cover plate having a pair 75 of ears respectively extending into the aforementioned apertures in said frame plates to support said cover between said frame plates and perpendicular thereto, said cover having a configuration corresponding to the aforesaid open end of said housing to enclose said open end and also having edge notches to receive electrical conductors adapted to be connected to the switching mechanism.

mentioned apertures in said frame plates to support said cover between said frame plates and perpendicular thereto, said cover having a configuration corresponding to the aforesaid open end of said housing to enclose said open end and also having edge notches to receive electrical conductors adapted to be connected to the switching mechanism, and a nut member threaded to the aforesaid collar and engaging said housing for maintaining the assembly rigid within said housing.

4. In an electric switch assembly which has a switching mechanism with an operating means therefor projecting therefrom, the combination of a pair of spaced parallel frame plates disposed on opposite sides of the switching mechanism and supporting the switching mechanism therebetween with the operating means extending out from one edge of each of said frame plates, a housing having a pair of spaced par- 15

10

allel sides and an open end for receiving said frame plates with the switching mechanism supported therebetween and with said frame plates disposed adjacent respective ones of the spaced parallel sides of said housing, said housing having an aperture in its end opposite said open end and through which the operating means for the switch mechanism protrudes, and an insulating cover plate secured to said frame plates and supported therebetween and perpendicular thereto, said cover plate having a configuration corresponding to the aforesaid open end of said housing to enclose said open end.
